 The Hoover Company, North Canton, Ohio, a
 corporation of Ohio

Application November 25, 1938, Serial No. 242,221

17 Claims. (Cl. 62—5)

This invention relates to the art of refrigeration and more particularly to a novel absorption refrigerating system and an evaporator for use therewith.

It is a principal object of the invention to provide a refrigerating system including an evaporator having distinct ice-freezing, box-cooling, and fast-freezing sections which are compactly and efficiently arranged and are associated with a receptacle for the continuous production and storage of ice and a low temperature refrigeration chamber.

It is a further object of the invention to provide a refrigerating system having a plurality of evaporator sections which are arranged to be individually supplied with liquid refrigerant from a common condenser in alternate periods and in which the control of the flow of liquid refrigerant from the condenser into the various sections of the evaporator is regulated by the production of ice in the evaporator and by the diversion of waste products of combustion from a boiler heater.

It is a further object of the invention to provide a refrigerating system of the type above referred to in which one section of the evaporator is arranged to favor production of refrigeration in a low temperature storage compartment and another section of the evaporator is arranged to favor refrigeration in an ice-freezing section thereof.

It is a further object of the invention to provide a refrigerating system having a plurality of evaporators connected in a single inert gas circuit and provided with individual refrigerant supplies which are so constructed and arranged that there is no possibility of liquid refrigerant discharged into one section of the evaporator finding its way into another section thereof.

It is a further object of the invention to provide a refrigerating system including an evaporator so constructed and arranged that it is provided with rear box-cooling sections, forwardly projecting ice making and low temperature storage compartment refrigerating elements.

Other objects and advantages of the invention will become apparent as the description proceeds when taken in connection with the accompanying drawings, in which:

Figure 1 is a diagrammatic representation of a refrigerating system embodying my invention in which the evaporator and associated control elements are shown on an enlarged scale and in perspective.

Figure 2 is a diagrammatic partial sectional

view on an enlarged scale of certain control mechanisms.

Referring now to the drawings in detail and first to Figure 1 thereof, the refrigerating system comprises a boiler B, an analyzer D, a tubular air-cooled condenser C, an evaporator E, a gas heat exchanger G, a tubular inclined air-cooled absorber A, a liquid heat exchanger L, and a circulating fan F which is driven by an electrical motor M. These elements are suitably connected by various conduits to form a complete refrigerating system including a plurality of gas and liquid circuits to which reference will be made in more detail hereinafter.

15 The refrigerating system above described will be charged with a suitable refrigerant, such as ammonia, a suitable absorbent, such as water, and an inert pressure equalizing medium, preferably a dense inert gas, like nitrogen.

20 The boiler B is arranged to be heated by a suitable combustible fuel burner H. The fuel burner H and the electrical motor M will be controlled in any suitable or desired manner by a control mechanism which is preferably responsive to 25 temperature conditions within the storage compartment of the refrigerator. A preferred control mechanism is illustrated and described in my co-pending application, Serial No. 148,424, filed June 16, 1937, now Patent No. 2,228,343, issued 30 January 14, 1941.

The application of heat to the boiler B generates refrigerant vapor from the solution therein contained. The vapor so generated passes upwardly through the analyzer D in counterflow relationship to strong solution flowing downwardly therethrough. In the analyzer further refrigerant vapor is generated from the strong solution by the heat of condensation of absorption solution vapor formed in the boiler. The refrigerant vapor is conveyed from the analyzer to the upper portion of the condenser by the conduit 11 which includes the air-cooled rectifier R.

45 The weak solution formed in the boiler is conveyed therefrom through the conduit 13, the outer path of the liquid heat exchanger L and the finned solution cooling conduit 14 into the lean solution reservoir 16. The lean solution in the reservoir 16 is conveyed from the bottom portion 50 thereof into the upper portion of the absorber A by a gas lift conduit 17. It is apparent that the upper portion of the absorber A is at an elevation appreciably above the liquid level normally prevailing in the boiler-analyzer system wherefore some means must be provided to ele-

vate the liquid refrigerant thereinto. For this purpose a small bleed conduit 18 is connected between the discharge conduit 19 of the circulating fan F and the gas lift pump conduit below the liquid level normally prevailing therein, whereby the lean solution is elevated into the absorber by gas lift action. The reservoir 16 is vented to the upper portion of the absorber by a small conduit 20.

The lean solution flows downwardly through the absorber in counterflow relationship to a rich mixture of pressure equalizing medium and refrigerant vapor flowing upwardly therethrough. The refrigerant vapor content of the mixture is absorbed by the solution and the heat of absorption is rejected to cooling air flowing over the outer surfaces of the absorber conduit and the air-cooling fins mounted thereon. The strong solution formed in the absorber is drained from the bottom portion thereof into the upper portion of the analyzer D by means of the conduits 21, the inner path of the liquid heat exchanger L and the conduit 22.

The lean inert gas mixture formed in the absorber is conveyed from the upper portion thereof into the suction eye of the circulating fan F by the conduit 24. The inert gas is placed under pressure by the circulating fan and is discharged through the conduit 19 which opens into the inner path of the gas heat exchanger G from which the inert gas is conveyed by the conduit 25 into the evaporator E. The exact construction and operation of the evaporator will be described more fully hereinafter. For the present it is sufficient to note that the inert gas circulates therethrough and is discharged through the conduit 26 into the outer path of the gas heat exchanger G from which it is conveyed by means of the conduit 27 into the bottom portion of the absorber A through which it flows counter to the absorption solution in the manner heretofore described.

The evaporator E comprises a pair of vertically spaced horizontally extending large diameter box-cooling conduits 30 and 31 which are provided with air-cooling fins 29. A pair of ice-freezing evaporator conduits, which are designated on the right and left-hand sides of the drawing, respectively, as 32 and 33, project horizontally forward from the right and left hand ends of the box-cooling conduit 30 and terminate in downwardly projecting return bent portions 34 and 35, respectively, which join rearwardly extending horizontal fast-freezing evaporator conduits 36 and 37, respectively. The conduit 36 terminates in the top portion of the right-hand end of the box-cooling conduit 31, and the conduit 37 joins the inert gas supply conduit 25. The left-hand end of the box-cooling conduit 31 joins the inert gas discharge conduit 26.

The ice-freezing evaporator conduits 32 and 33 are provided with a plurality of inclined spaced apart freezing plates 40 which are adapted to receive the inclined bottom portion of a water tank 42. The bottom portion of the water tank rests upon an insulated fast-freezing compartment 38 which embraces the fast-freezing conduits 36 and 37 in its top portion. The fast-freezing conduits 36 and 37 are separated from the storage space within the insulated compartment 38 by means of a horizontal top wall plate 39.

Though the shallow tank 42 has been shown as being exposed so that it may be contacted by air within the refrigerator cabinet, it may be

completely enclosed in insulating material which preferably would extend upwardly from and integral with the insulation of the fast-freezing compartment 38. Of course the top portion of the tank 42 will not be insulated but it may be provided with an insulated removable cover.

The refrigerant vapor which is liquified in the condenser discharges therefrom through a conduit 44 into the top portion of a diversion chamber 45. The bottom portion of the diversion chamber 45 is divided into two sections by an upstanding partition wall 46. A drain conduit 47 including a downwardly extending U-shaped liquid sealing portion connects the right hand side of the partition 46 with the ice-freezing evaporator conduit 32. A drain conduit 48 which also includes a downwardly extending U-shaped liquid sealing portion communicates the left-hand side of the partition 46 with the gas inlet portion of the fast-freezing conduit 31. The diversion chamber and the conduits 47 and 48 are vented to the inert gas conduit 25 by a small conduit 49.

The right-hand side of the box-cooling conduits 30 and 31 are connected by a small diameter drain conduit 50 which includes a U-shaped liquid sealing portion. The inert gas outlet end of the box-cooling conduit 31 is provided with a drain conduit 51 which communicates with the strong solution return lines 21 below the liquid level normally prevailing therein.

The boiler B is provided with a waste products of combustion flue 55 which terminates in a diversion box 56 at a level slightly below the level 35 of the evaporator structure. The diversion box 56 is provided with a vertically extending discharge flue 57 and a laterally extending discharge flue 58. A flap valve 59 is pivotally mounted within the chamber 56 in such position that it 40 may be swung to prevent flow of waste products of combustion through either of the discharge conduits 57 and 58.

The flap valve 59 is actuated by means of a crank 60 which is pivotally connected to the actuating element of an overcenter snap action mechanism 64 housed within a control box 65. A pair of pressure responsive bellows 67 and 68 are mounted in the left and right-hand sides, respectively, of the casing 65, as viewed in Figure 2. The bellows 67 is connected by means of a capillary conduit 70 to a bulb element 71 which is positioned within the tank 42 in position to be frozen into an ice block forming on the interior wall of that tank over one of the plates 40 on the ice-freezing evaporator conduit 33. The bellows 68 is connected with a capillary conduit 72 which terminates in a bulb element 73 which is positioned within the tank 42 in position to be frozen into an ice block forming on the interior wall thereof in contact with one of the plates 40 on the ice-freezing evaporator conduit 32. The bellows 67 and 68 are positioned to actuate the overcenter mechanism 64, thereby to actuate the flap valve 59.

The products of combustion discharge flue 58 extends upwardly as illustrated and receives a thermostat housing 75 which projects laterally from the diversion chamber 45 and extends about half way through the conduit 58. A spiral bi-metallic thermostat 76 is mounted within the chamber 75 and is connected to actuate the shaft 77 of a diversion plate 78 mounted within the diversion chamber 45. The diversion plate 78 is mounted in such relation to the condensate discharge conduit 44 and the dividing

wall 46 that liquid discharging through the conduit 44 may be directed wholly to one side or the other of the plate 46 whereby the same is wholly diverted into conduit 47 or 48.

The above described mechanism will be enclosed in a suitable cabinet preferably with the refrigerating mechanism suitably distributed in a lower mechanism compartment and a rear vertically extending air-cooling flue with the exception, of course, of the evaporator which will preferably be positioned in the top central portion of the food storage compartment.

The evaporator will preferably project forwardly in the apparatus whereby the front opening, which will be closed by a suitable insulated door, of the compartment 38 is readily accessible from the front portion of the box and the water tank 42 may be rendered accessible by a small pivoted panel in the top portion of the refrigerator cabinet. This construction will place the box-cooling evaporator conduits 30 and 31 in the rear of the storage compartment adjacent the rear wall thereof.

The operation of the invention is as follows: Assuming that the apparatus has not been operated and that the refrigerator is warm, the normal control mechanism will energize the heater H and the circulator motor M to place the refrigerating system in operation. There being no ice in the water tank, the expandible thermostatic elements 67 and 68 will both be moved to their expanded position but the snap-action mechanism will be in one or the other of its two possible positions.

Assuming that the apparatus is warm and that the flap valve 59 is in the position shown in Figure 2, the products of combustion from the boiler heater will discharge through the conduit 57 and no heat will be applied to the thermostatic element 76 because there will be no waste products of combustion flowing through the conduit 58. Under these conditions, the thermostat 76 will have actuated the diversion plate 78 to the position illustrated to discharge the liquid refrigerant flowing from the conduit 44 into the conduit 47. This liquid refrigerant will flow into the evaporator conduit 32 through which it will be propelled by the inert gas stream through the conduits 32, 34 and 36. Any refrigerant unevaporated in these conduits will flow into the conduit 31 where it will be evaporated to produce refrigeration for purposes of box-cooling at a relatively high temperature.

This operation of the apparatus will continue until ice blocks of a predetermined size have been formed within the tank 42 on those wall portions thereof which are in heat exchange relationship with the plates 40 on conduit 32. When the ice blocks have reached the above-mentioned predetermined size, the bulb element 73 will freeze therein which will cause the thermostatic element 68 to collapse, whereupon the over-center mechanism 64 will be actuated by the expanded thermostatic bulb element 67 to operate the flap valve 59 in a clockwise direction to shut off communication between the conduit 57 and the chamber 56 and to permit products of combustion flowing through the discharge flue 55 to exit through the conduit 58.

The products of combustion flowing through the conduit 58 will heat the thermostat 76 which will then actuate the diversion plate 78 in a clockwise direction whereupon all refrigerant liquid thereafter discharged will flow into the conduit 48 and will be discharged into the fast-

freezing evaporator conduit 37. This liquid refrigerant will be projected through the conduits 37, 35 and 33 by the rapidly flowing inert gas stream and will produce refrigeration in those conduits. Any refrigerant liquid which is not evaporated in the conduits 37, 35 and 33 will flow into the box-cooling conduit 30 in which it will evaporate into the inert gas stream to produce refrigeration for box-cooling purposes.

10 This operation of the apparatus will continue until ice blocks of a predetermined size have been formed on those portions of the inner wall of the tank 42 which are in heat exchange relationship with the plates 40 on the conduit 33. 15 When the ice blocks reach the above mentioned predetermined size, one of them will freeze around the bulb 71 which will cause the thermostatic element 67 to collapse. If now the ice blocks previously formed on the side of the tank 42 which is refrigerated by the evaporator conduit 32 have melted free thereof, the bulb 68 will have expanded and will immediately actuate the snap-acting mechanism to the position illustrated in Figure 2 when the thermostat 67 collapses. This will again cut off communication between the conduits 55 and 58, the thermostat 76 will cool, and the plate 78 will be actuated back to the position illustrated to again discharge liquid refrigerant into the conduit 47.

20 Therefore, refrigeration is alternately produced in the right and left-hand sides of the evaporator and in the upper and lower box-cooling evaporator conduits.

25 The evaporator conduits 32, 34, 36, 37, 35 and 33 are of relatively small diameter with respect to the quantity of gas discharged therethrough whereby the gas flows through these conduits at a velocity sufficiently high to sweep or drag the liquid refrigerant therethrough as it is evaporating into the inert gas stream. Apparatus and methods by which the liquid refrigerant is propelled through an evaporator by the frictional dragging action of the inert gas flowing through the evaporator are disclosed and claimed in the co-pending application of Curtis C. Coons and William H. Kitto, Serial No. 386,395, filed April 2, 1941.

30 The evaporator conduits 31 and 30 will be inclined slightly to permit the liquid refrigerant to flow therethrough by gravity as the inert gas flows through these large diameter conduits too slowly to exert any propelling action on the liquid refrigerant.

35 With the evaporator arrangement herein disclosed, the right hand side of the forwardly projecting portions of the evaporator first produce refrigeration in contact with the water tank thereby favoring the production of ice, whereas those portions of the evaporator projecting forwardly on the left-hand side of the apparatus first produce refrigeration in the conduit 37 which is in heat exchange relationship with the low temperature fast-freezing compartment 38, thereby favoring refrigeration for that purpose.

40 Each of the individually operated evaporator sections produces refrigeration for box-cooling purposes in approximately the same quantity and for the same period of time. However, it should be noted that the refrigeration demands of the compartment 38 are relatively small because, first, this compartment is of small size, secondly, it is heavily insulated, and thirdly, it is not ordinarily called upon to carry any very large refrigerating load though it is perfectly capable

of assuming a heavy load, as for dessert freezing purposes.

The above described operation of the apparatus will continue so long as the normal control for the burner H and the motor M has energized these elements in response to the demand for refrigeration in the storage compartment of the refrigerator. Therefore, as a result of this action there is a continuous production of ice in the form of individual blocks which float freely on the surface of a body of water in the tank 42 and which may be removed at any time in any desired number by the simple process of ladling the blocks from the water in the tank 42.

The control of this particular apparatus automatically tends to gear the production of ice to seasonal demands. This is achieved as follows: During periods of warm weather the heat leakage into the storage compartment of the refrigerator will increase whereupon the normal control mechanism will cycle the apparatus more frequently which will result in a more frequent production of ice cubes. On the other hand, in periods of cool weather the heat losses through the refrigerator cabinet will not be so great, the apparatus will cycle less frequently, and a lesser number of ice blocks will be produced. Therefore, the apparatus automatically produces a greater quantity of ice during periods of warm weather when ice is in greater demand by domestic users.

The control mechanism is so constructed and arranged that neither of the bellows 67 and 68 is able to actuate the over-center mechanism 64 from one position to the other if the opposing bellows is also expanded; that is, it requires that one of the bellows 67 and 68 collapse before the over-center mechanism is enabled to change the position of the flap valve 59. This, therefore, insures that ice blocks of a predetermined size will be formed in the operative portion of the ice freezing evaporator without interference even though ice blocks on the inoperative side of the ice freezing evaporator have melted free from the bottom walls thereof and the associated bellows has expanded.

Though specific constructions have been described in detail herein, obviously the invention is not limited thereto. For example, other forms and arrangements of thermostatic mechanisms might be utilized with equal effectiveness, and the evaporator conduits might be arranged in a different fashion. For example, the position of the water tank 42 and of the insulated fast-freezing compartment 38 could be reversed, if desired, thereby joining the insulated top wall of the compartment 38 with the insulated top wall of the refrigerator cabinet. Additionally, the thermostatic element governing the operation of the diversion plate 78 could be operated by alternately permitting warm air flowing from the heat rejecting condenser and/or absorber to contact the same, thereby achieving essentially the same control as that specifically described herein.

The present invention provides a highly convenient and efficient apparatus whereby ice may be produced continuously and stored in a refrigerated atmosphere until needed. Additionally, the apparatus provides a construction whereby ice is alternately produced in different refrigerating zones and the control is achieved in response, first, to demands for production of ice in the different zones, and secondly, by controlling the path of flow of waste products of combustion generated in the boiler.

The evaporator construction herein disclosed and claimed is additionally advantageous for the reason that refrigeration is produced in the box-cooling conduits 30 and 31 at relatively high temperatures whereby the air within the refrigerating compartment is maintained at safe values for food storage but without material or objectionable drying thereof by reason of the relatively high temperatures at which the evaporators 30 and 31 operate. The high temperature operation of these evaporators is assured by reason of the fact that each of these evaporators is supplied with gas which has already passed through the primary evaporating zones in the fast-freezing and ice production evaporator sections, whereby the refrigerant must evaporate at higher temperatures in the box-cooling conduit.

While the invention has been illustrated and described herein in considerable detail, it is not to be considered as being limited thereto as various changes may be made in the construction, proportion and arrangement of parts without departing from the spirit of the invention or the scope of the appended claims.

I claim:

1. Refrigerating apparatus comprising an evaporator including a pair of finned space cooling elements, a pair of freezing elements, means connecting said elements in series, means for propelling an inert gas through said elements, liquid refrigerant supply means, and means for selectively directing liquid refrigerant into a selected portion of said evaporator in order to render only one of said box-cooling elements and one of said ice-freezing elements operative.

2. Absorption refrigerating apparatus comprising a solution circuit including a boiler and an absorber, an inert gas circuit including said absorber and an evaporator, means for heating said boiler, means for supplying refrigerant vapor generated in said boiler to said evaporator in liquid phase, said evaporator comprising a plurality of individual ice-freezing sections each of which is mounted in heat exchange relationship at a plurality of points with a body of material to be frozen, means for directing the liquid refrigerant supplied to said evaporator into a selected one of said evaporator sections, thermostatic means for operating said directing means, and means operated in response to demand for refrigeration within parts of the said body of material to be frozen which are in heat exchange relationship with said evaporator sections for allowing or preventing heat exchange between said thermostatic means and waste heat from said boiler.

3. Absorption refrigerating apparatus including an evaporator having a plurality of sections each of which is in heat exchange relationship at a plurality of points with a body of material to be frozen, liquid refrigerant supply means, means for directing liquid refrigerant from said supply means into a selected one of said evaporator sections, thermostatic means for controlling said directing means, and refrigeration demand responsive means for allowing or preventing actuation of said thermostatic means by waste heat from said refrigerant supply means.

4. Refrigerating apparatus including an element from which warm gas is discharged, an evaporator having a plurality of individual freezing sections, liquid refrigerant supply means, thermostatic means for directing liquid refrigerant from said supply means into a selected one of said evaporator sections, and refrigeration de-

mand responsive means constructed and arranged to allow or to prevent heat exchange between said warm gas and said thermostatic means to control said diverting means.

5. An absorption refrigerating apparatus of the type utilizing a boiler and a combustible fuel burner therefor, an evaporator comprising a first-freezing element, a first space cooling element, a second freezing element, a second space cooling element, said elements being serially connected in the order named, means for propelling a pressure equalizing medium through said elements serially in the order named, said system including liquid refrigerant supply means, and refrigeration demand responsive means operative to direct said liquid refrigerant wholly into either said first elements or said second elements as may be required.

6. Absorption refrigerating apparatus including a boiler, a combustible fuel burner for heating said boiler, a refrigerant vapor liquefying means, an evaporator comprising a plurality of sections each of which includes associated freezing and box-cooling elements, thermostatic means for directing liquid refrigerant from said liquefying means into a selected one of said sections, and refrigeration demand responsive for directing or preventing flow of waste products of combustion from said fuel burner in heat transfer relationship with said thermostatic means.

7. Absorption refrigerating apparatus comprising liquid refrigerant supply means including a boiler, combustible fuel burning means heating said boiler, refrigerant liquefying means, a first evaporator element including a freezing coil and a space cooling coil, a second evaporator element including a freezing coil and a space cooling coil, means for propelling a pressure equalizing medium serially through said first and second evaporator elements, thermostatic means for directing liquid refrigerant from said liquefying means wholly into one or the other of said evaporator elements, a discharge flue having two branches constructed and arranged to convey waste products of combustion from the boiler-heater either in heat transfer relationship with said thermostatic means or directly to waste, and refrigeration demand responsive means for governing said last-mentioned means.

8. Absorption refrigerating apparatus comprising means for producing refrigerant liquid including a heated element, means for heating said element, a plurality of evaporating elements, means for directing liquid refrigerant generated by said apparatus to a selected one of said evaporating elements, and refrigeration demand responsive means operative to allow or to prevent the discharge of waste heat from said heating means into heat transfer relationship with said directing means.

9. Refrigerating apparatus comprising an evaporator including vertically spaced rear box-cooling conduits, forwardly projecting ice freezing evaporator sections, and forwardly projecting low temperature refrigerating evaporator conduits, all of said elements being serially connected, liquid refrigerant supply means, and means for directing liquid refrigerant into a selected evaporator section.

10. Refrigerating apparatus comprising a cooling unit including a pair of spaced box-cooling sections, a pair of U-shaped chilling sections each of which has one leg connected to one of said box-cooling sections, one of said chilling

sections being connected to the other of said box-cooling sections, means for supplying a pressure equalizing medium to the chilling section not connected to said other box-cooling section, and means for selectively supplying refrigerant to the pressure equalizing medium inlet portions of said chilling sections.

11. Refrigerating apparatus comprising a refrigerant supply means including a boiler and a heater therefor, a plurality of evaporators, means for directing refrigerant from said supply means into a selected evaporator, thermostatic means for operating said directing means, and means for directing waste heat from said heating means into and out of thermal relationship with said thermostatic means.

12. Refrigerating apparatus comprising an evaporator including a pair of finned box-cooling coil elements, a pair of ice-freezing coil elements operatively associated with said box-cooling coil elements, liquid refrigerant supply means, and means for directing liquid refrigerant from said supply means into a selected portion of said evaporator to render only a selected box-cooling element and a selected ice-freezing element operative.

13. Refrigerating apparatus comprising a pair of cooling units, a water container in heat transfer relationship therewith, an insulated chamber, a cooling unit serially connected to each of said first-mentioned cooling units and mounted in said insulated chamber, a finned space cooling unit serially connected to each of said first mentioned cooling units, a finned space cooling unit serially connected to one of said second mentioned cooling units and refrigeration demand responsive means for supplying cooling medium to a selected group of said cooling units.

14. Absorption refrigerating apparatus comprising a solution circuit including a boiler and an absorber, a pressure equalizing medium circuit including an evaporator and said absorber, a combustible fuel burner for heating said boiler, said evaporator comprising two units each of which includes box-cooling, ice-freezing and low temperature refrigerating sections, means for supplying refrigerant vapor generated in said boiler to said evaporator in liquid phase, directing means for directing such refrigerant liquid to a selected one of said units, a flue for waste products from said boiler having two branches, refrigeration demand responsive means for controlling the flow of waste products of combustion through said flue branches, and thermostatic actuating means for said directing means in one of said branches.

15. Refrigerating apparatus comprising a cooling unit including a pair of spaced box-cooling sections, a pair of U-shaped chilling sections each of which has one leg connected to one of said box-cooling sections, one of said chilling sections being connected to the other of said box-cooling sections, and means for supplying a pressure equalizing medium and a cooling medium to said cooling unit.

16. Absorption refrigerating apparatus comprising a generator, a condenser, an evaporator and an absorber connected to form a refrigerating system including a plurality of paths of flow of fluid, a combustible fuel burner arranged to heat said generator, means providing a plurality of paths of flow of waste products from said fuel burner, fluid flow control means in said system to control at least one of said paths of flow of fluid, thermostatic means for actuating said fluid

flow control means arranged in heat transfer relationship with one of said paths of flow of waste products, and means for directing waste products from said generator into a selected one of said paths of flow of waste products.

17. Refrigerating apparatus comprising a cooling unit, a source of cooling medium, said cooling unit including a first chilling element, a first space cooling element serially connected to said

first chilling element, a second chilling element, a second space cooling element serially connected to said second chilling element, means for directing cooling medium from said source wholly into one of said first elements or into one of said second elements and refrigeration demand responsive means for operating said directing means.

CURTIS C. COONS.
